CLAIM

The ornamental design for a combined knife handle and blade holder therefore, as shown.

DESCRIPTION

FIG. 1 is a side elevational view of a combined knife handle and blade holder therefor showing our new design;

FIG. 2 is a bottom plan view thereof;

FIG. 3 is a top plan view thereof;

FIG. 4 is an elevational view of the other side thereof;

FIG. 5 is a front end elevational view thereof; and

FIG. 6 is a rear end elevational view thereof.
